UNITED STATES PATENT OFFICE

1,995,426

SLUR ELIMINATOR FOR PRINTING PRESSES

Hans Honigmann, Cleveland, Ohio, assignor to
The Chandler & Price Company, Cleveland,
Ohio, a corporation of Ohio

Application May 5, 1932, Serial No. 609,456

12 Claims. (Cl. 101—250)

This invention relates, as indicated, to printing presses, but has reference more specifically to a device which is particularly adapted for use in a printing press of the bed and cylinder type for the purpose of eliminating or preventing the slurring with ink of the sheet which is being printed by the last line of type in the chase or type form.

In the use of bed and cylinder type printing presses, such, for example, as disclosed in Patent No. 1,774,272, granted to me August 26, 1930, it has been observed that when relatively stiff sheets, such as cardboard, are being printed, the trailing end of such sheets does not cling to the tympan on the cylinder, but tends to straighten out, with the result that such trailing end of the sheet drags across the last line of type in the chase and is slurred by ink therefrom.

The invention has as its object the provision of a device which may be quickly and easily inserted in the type form or chase, and which shall be effective to prevent the slurring in the aforesaid manner of the sheet which is being printed.

Another object of the invention is to provide a device of the character described, which shall be inoperative at all times, except during the printing of the last line or lines of type. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a fragmentary sectional view through the cylinder and a portion of the bed of a printing press, showing the sheet receiving position of the cylinder, Fig. 2 is a plan view of the chase or type form; Fig. 3 is a fragmentary sectional view, showing the manner in which the trailing end of the sheet is raised to prevent the slurring thereof by the last line of type; Fig. 4 is a fragmentary longitudinal cross-sectional view through the slur eliminator, with the sheet lifting bar thereof in inoperative position; Fig. 5 is a transverse cross-sectional view through the slur eliminator, taken on a plane substantially indicated by the line 5—5 of Fig. 4; and Fig. 6 is a view similar to Fig. 4, but showing the sheet lifting bar in operative position.

Referring more particularly to the drawing, 1

is the top of the main frame of the printing press, on which the bed 2 that carries the chase or type form 3 is mounted for reciprocal movement by pinion 4. The pinion 4 is secured to a shaft 5, which is suitably journaled in the main frame of the press.

The bed 2 is provided at one side with an upwardly projecting rack 6, which is in mesh with a gear 7 fixed on the end of the shaft 8, on which the cylinder 9 is mounted, so that reciprocal movement of the bed of the press results in oscillatory movement of the cylinder.

The cylinder 9 is a hollow drum with a smooth exterior surface save for recesses 10 in which are received the clamping devices 11 that serve to secure the tympan 12 in taut condition on the sheet carrying portion of the cylinder. The recesses 10 also serve to receive gripper fingers 13, the outer ends of which project over the adjacent edge of the sheet carrying portion of the cylinder to grip thereto a sheet of paper when properly placed thereon.

Positioned within a frame 14 on the bed 2 of the press is the chase or type form 15, in which the rows of type 16 are locked by means of suitable lock-up bars and wedges. Positioned in the type form 15 between certain of these lock-up bars 17 and 18 is the slur eliminating device of the present invention.

The slur eliminator comprises a stationary holder bar 19, in the ends of which are recesses 20, within which levers 21 are mounted for pivotal movement about pins 22 in the holder bar. The levers 21 are provided with arms 23, which extend substantially at right angles to the levers 35 and are disposed over the sides of the chase 15, and with toe portions 24, which underlie the heads of screws 25. Screws 25 extend through recesses 26 in the bar 19 and are secured to a sheet lifting bar 27, which is disposed directly above the bar 19. The bar 27 is normally maintained in its operative position, shown in Figs. 1 and 4, by means of coil springs 28, which are disposed within recesses 29 in the bar 19 and about the heads of the screws 25. In this position, the upper surface of the arms 23 of the levers 21 is slightly above the face of the type in the chase 15.

A sheet of paper, designated S in Fig. 3 is moved downwardly on inclined feed table 30 by means of sets of endless tapes 31 and 32 to a position in which its forward end may be attached to cylinder 9 by gripper fingers 13. The bed 2 of the press is then moved to the left, as viewed in Fig. 1, and the cylinder 9 is simultaneously rotated in a clockwise direction, as indicated. The

sheet S is wrapped around the cylinder, as the latter rotates, and at the same time is pressed in contact with the type in the chase 15.

If the sheet S is of relatively stiff paper, such as cardboard, its trailing free end, as shown in Fig. 3 does not cling to the tympan 12, but remains substantially straight, with the result that the sheet is likely to be slurred by the dragging of the sheet across the last line of type.

10 Such slurring is avoided in the following manner:

As the trailing end of the sheet approaches the last line of type, the arms 23 of the levers 21 are depressed by the tympan 12 of the cylinder, thereby lifting the bar 27 to its operative position, shown in Figs. 3 and 6, wherein it engages the trailing end of the sheet and maintains it in contact with the tympan, so as to prevent the dragging of the sheet across the type. The arms 23 are of sufficient length to maintain the trailing end of the sheet in engagement with the tympan until the last line of type has been printed and the possibility of the sheet dragging across the last line of type is no longer present.

25 After the bar 27 has passed the position shown in Fig. 3, it resumes its normal inoperative position, so that when the type is subsequently supplied with ink from suitable inking rolls (not shown), the upper surface of the bar will not be inked by such rolls.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. The combination with a printing couple comprising a reciprocable bed for carrying the form and a cylinder for carrying the sheet to be printed; of a type form, containing the type, and a slur eliminating bar disposed in said form comprising a vertically movable bar, and means actuated by the cylinder to move the bar to a position in which its upper surface is substantially flush with the face of the type.

2. The combination with a printing couple comprising a reciprocable bed for carrying the form and a cylinder for carrying the sheet to be printed; of a type form, type set within said form, a lock-up bar within said form, and adjacent the last line of type, a vertically movable bar adjacent said lock-up bar, and means adapted when suitably actuated to move said bar upward to a position in which its upper surface is substantially flush with the face of the type.

3. The combination with a printing couple comprising a reciprocable bed for carrying the form and a cylinder for carrying the sheet to be printed; of a type form, type set within said form, a vertically movable bar disposed within said form with its upper surface normally disposed below the type face level, and means for moving said bar to a position in which its upper surface is substantially flush with the type face level.

4. The combination with a printing couple comprising a reciprocable bed for carrying the form and a cylinder for carrying the sheet to be printed; of a type form, type set within said form, a vertically movable bar disposed within said form adjacent the last line of type and with its upper surface normally disposed below the type face level, and means for moving said bar to a position in which its upper surface is substantially flush with the type face level.

5. The combination with a printing couple comprising a reciprocable bed for carrying the form and a cylinder for carrying the sheet to be printed; of a type form, type set within said form, a vertically movable bar disposed within said form adjacent the last line of type and with its surface normally disposed below the type face level, and means movable by the cylinder to move the bar to a position wherein its upper surface is substantially flush with the type face level.

10 6. The combination with a type form containing set-up type, of a non-printing slur eliminating bar within said form having its upper surface normally disposed beneath the level of the type face, and means for raising said bar to a position in which said surface is substantially flush with said type face.

15 7. The combination with a type form containing set-up type, of a non-printing slur eliminating bar within said form, spring means normally biasing said bar to a position in which its upper surface is below the type face level, and means for overcoming the action of said spring means to raise said bar to a position wherein its upper surface is substantially flush with the type face level.

20 8. The combination with a type form containing set-up type, of a non-printing slur eliminating bar within said form having its upper surface normally disposed beneath the level of the type face, and levers for raising said bar to a position in which said surface is substantially flush with said type face.

25 9. The combination with a type form containing set-up type, of a stationary bar within said form, a movable non-printing slur eliminating bar mounted on said stationary bar, and means on said stationary bar for raising said movable bar to a position in which its upper surface is substantially flush with the level of the type face.

30 10. In a device of the character described, a bar, a second non-printing slur eliminating bar movable with respect to said first bar, and levers adapted to move the second bar away from the first bar.

35 11. In a device of the character described, a bar, a second non-printing slur eliminating bar movable with respect to said first bar, levers for moving the second bar away from the first bar, and spring means opposing such movement.

40 12. In a device of the character described, a bar, a second non-printing slur eliminating bar movable with respect to said first bar, levers pivotally mounted on said first bar and operable to move the second bar away from the first bar, and springs opposing the movement of said levers.
